UNITED STATES PATENT OFFICE.

EUGENE W. APPLEBAUM, OF CHICAGO, ILLINOIS.

SIGN FLASHER.

Application filed May 27, 1926. Serial No. 111,973.

The present invention relates to electric sign flashers, and particularly to those operating on alternating currents.

Difficulty has been encountered with the present commercial flashers, in that due to the art resulting from the making and breaking of the circuit, the brushes are rapidly burned up and there is a large replacement and repair cost.

10 The primary object of the present invention is the provision of a device which will eliminate arcing in the flasher.

Another object of the invention is the provision of a device of the class described which may be utilized with present commercial flashers without material change in their construction, this being accomplished by the addition of timing gears. Or, the device may be incorporated in the flashers 20 during the process of manufacture.

A further object of the invention is the provision of a sign flasher which is simple in construction, economical to manufacture, and certain in its operation.

25 That the invention may be better understood, reference is had to the accompanying drawings and the following description of a preferred embodiment thereof. It is to be understood that this disclosure is given for illustrative purposes only, and is not to be construed as limiting the scope of the protection sought as defined by the appended claims.

In the drawings

35 Fig. 1 is a diagrammatic view illustrating the herein described invention;

Fig. 2 is a detailed illustration, schematically illustrating certain of the gearing connections.

40 The device comprises a variable transformer regulator 11 in which a portion 12 of one core is separated from the main core and is rotatably mounted on the shaft 13.

The primary core 11^a is wound with the 45 primary winding 14 and the rotating portion 12 of the secondary core is wound with the secondary winding 15. The secondary core portions 11^b of the transformer are considerably larger than the primary core 11^a and are cut away at their ends to form the segments of the circle so that the rotating portion 12 of the secondary core may be mounted therebetween. A pair of slip rings 16 and 17 are fixedly mounted on the 50 shaft 13 and are connected to the secondary

winding 15, thus permitting the taking of current from the secondary winding when the same is in rotation. Brushes 18 and 19 are mounted on the slip rings 16 and 17 and from these brushes the current is taken to the flasher and the sign.

As the transformer may be utilized with most of the commercial flashers, a flasher has been conventionally illustrated. The flasher shown comprises a cam 21 which is 65 fixedly mounted on the shaft 22 and is provided with a series of brushes 23 which are adapted to engage lobes 24 of the cam. The lobes 24 are of varying length so that they connect with the brushes 23 in order. The 70 brushes 23 are connected with the sign 26 through the lead wires 25. The complete sign circuit is established through the wires 25, the wire 25^a which leads from the brush 18 on the slip ring 16 to one side of the 75 sign, and the wire 25^b which leads from the brush 19 to the cam 21.

The cam 21 is rotated in time with the secondary transformer core 12 through means of the gear 27, mounted on the shaft 80 22 and the gear 28 mounted on the shaft 13. The ratio of these gears is such that the secondary 12 will make a half revolution during the passage of each cam lobe past the brushes. The cam 21 is positioned in 85 relation to the secondary 12 so that the brushes 23 are in the middle of one of the lobes 24 when the core 12 is in alignment with the secondary core member 11^b and positioned at the end of one of the segments 90 when the core 12 is at right angles to the secondary core members 11^b. The entire device may be driven by a motor 29 which operates the shaft 13 through means of the worm gear 30 which is fixedly mounted on 95 the motor shaft and the gear 31 mounted on the shaft 13.

In operation the motor 29 rotates the shaft 30 which causes rotations of the slip rings 16 and 17, the secondary 12, the shaft 100 22, and cam 21. Current is supplied to the primary 14 of the transformer 11 from the main power lines, thereby inducing current into the secondary 12 when the latter is in alignment with the pole pieces 11^b. 105 As the secondary 12 approaches a position at right angles to the pole pieces 11^b the current induced therein approaches zero and as the secondary continues its rotation the current raises to its peak as the sec- 110

ondary approaches and is again in alignment with the pole pieces 11^b. As has been pointed out the brushes 23 will be making or breaking the sign circuit when the secondary 12 is in the zero position, consequently there will be no arc at the brushes.

The stationary portions 11^b of the secondary core, as above noted, are made considerably larger than the primary core 11^a and are cut away to form segments of a circle. The ends of the upper segment approaching the corresponding ends of the lower segment and separated therefrom a distance which is approximately that of the width of the ends of the rotating portion 12 of the secondary core. By this construction smoother operation of the device is secured.

As has been pointed out, the invention is susceptible of embodiment in many forms, and the foregoing disclosure is to be construed as purely illustrative of the principle involved, for with it in mind, the physical embodiment of the invention in suitable apparatus may vary with the use to which the apparatus is to be put and can be constructed by anyone skilled in the electrical art.

I claim:

- 30 1. The combination with a sign flasher mechanism of an electric circuit, a second circuit inductively coupled to the first circuit, said flasher mechanism being included in said second circuit, and means for varying the coupling of said circuits, said means being so timed as to decrease the coupling of the said circuits when the flasher mechanism is in making or breaking position.
- 40 2. A sign flasher comprising a flasher mechanism, a transformer associated with said mechanism, said transformer having a rotatable core, means for rotating said core to place the same in non-inductive position when the flasher mechanism is in making or breaking position, and means for establishing electrical connection between said rotatable core and said flasher mechanism.
- 50 3. A sign flasher comprising a flasher mechanism, a transformer associated with said flasher mechanism, said transformer having one winding rotatably mounted, means for rotating said winding to place the same in non-inductive position when the flasher mechanism is in making or breaking position and means for electrically connecting said rotatable winding with said flasher mechanism.
- 60 4. A sign flasher comprising a flasher mechanism, a transformer electrically connected with said flasher mechanism, said transformer having a stationary primary and a rotatable secondary, timing mechanism for placing said secondary in non-inductive position when the flasher mechanism is in making or breaking position.

5. A sign flasher comprising a flasher mechanism, a transformer associated with said flasher mechanism, said transformer having a stationary primary and a rotatable secondary, means for taking the current from said secondary to the flasher mechanism, and means placing the secondary in non-inductive position when said flasher mechanism is in making or breaking position.

6. The combination of a sign flasher with means for varying the current through said flasher, said means comprising a transformer having a fixed primary, a rotatable secondary and slip rings for taking the current from said secondary and means for placing the secondary in non-inductive position when the flasher mechanism is in making or breaking position.

7. A sign flasher comprising a flasher mechanism, a transformer having a rotatable secondary, timing gears connecting said rotatable secondary and said flasher mechanism said timing gears being in such ratio as to place the secondary in non-inductive position when the flasher mechanism is in making or breaking position, slip rings associated with said rotatable secondary, brushes engaging said slip rings, and current connections for taking the current from said slip rings to an electric sign and through said flasher mechanism.

8. The combination of a sign flasher with inductively coupled means for varying the current through said flasher from zero voltage to peak load, and timing mechanism connecting said flashing mechanism and said inductively coupled means for decreasing the coupling of the inductively coupling means when the flasher mechanism is in making or breaking position.

9. The combination of a sign flasher with a transformer, said transformer having a rotatable winding, core pieces between which said winding rotates, said core pieces substantially surrounding said rotatable winding and means for timing the action of said transformer with said sign flasher so as to place said rotatable winding in non-inductive position when the flasher is in making or breaking position.

10. A sign flasher comprising a cam, lobes of varying length extending from said cam, brushes adapted to engage said lobes, a transformer, means for varying the coupling of the primary and secondary of said transformer and means for driving said cam and said transformer in timed relationship so as to place the secondary of said transformer in non-inductive position when said sign flasher is in making or breaking position.

11. The combination of a sign flasher mechanism with a transformer, said transformer having a stationary primary, a rotatable secondary, core pieces substantially sur-

rounding said secondary and means for rotating said rotatable secondary in time with said flasher mechanism so as to place the secondary of said transformer in non-inductive position when said sign flasher is in making or breaking position.

12. The combination of means for interrupting an electric circuit with inductively coupled means for varying the current through said interrupting means from zero voltage to peak load, and timing mechanism connecting said interrupting means and inductively coupled means for placing said inductively coupled means in non-inductive position when said interrupting means is in making or breaking position.

13. The combination of means for interrupting an electric circuit, with a transformer electrically connected with said interrupting means, said transformer having a stationary primary and rotatable secondary, and timing mechanism for placing said secondary in non-inductive position when the interrupting means is in making or breaking position.

In testimony whereof I have hereunto subscribed my name.

EUGENE W. APPLEBAUM.
